SPRING ASSEMBLY

George E. Taylor, Chicago, Ill., assignor to Samuel E. Sosna and George E. Taylor, jointly, as trustees

Application March 1, 1943, Serial No. 477,560

11 Claims. (Cl. 5—275)

This application is a continuation in part of my copending application, Serial No. 470,252, filed December 26, 1942.

This invention relates to the construction of spring cushions of the character employed in couches, chair cushions, box type bed springs and the like, and more particularly it relates to the construction of the spring assembly unit apart from the upholstery which may subsequently be applied thereto.

In the construction of spring structures of the aforesaid character it is essential that the spring assembly possess the desired degree of resiliency when the load is distributed thereon over a relatively large area and in a particular manner, and yet, the construction of the spring assembly must be such that sufficient strength and resiliency is afforded to support a corresponding load applied thereto over a relatively small area of the top of the spring area. To attain this desired functioning of spring assemblies of the character to which this invention relates it has been customary to utilize vertically positioned coil springs mounted on a relatively rigid bottom frame and disposed in closely spaced longitudinal and transverse rows on such frames so that, with the exception of the marginal springs along one or more of the edges of the assembly, the resilient weight-supporting action of each coil spring has been substantially independent of the adjacent springs. With respect to the marginal springs of such assemblies it has been customary to employ a border wire or frame extended along and connected to the outer edges of the upper, flat convolutions of the marginal springs, thereby to afford a more definite and positive support along the edge of the spring assembly, but such border wires or frames have had as their principal object the provision of resistance to lateral or inward distortion of the marginal springs. While such border wires have functioned to a limited extent to distribute load to several of the adjacent springs, such distribution has in every instance been relatively inefficient, since the border wire or frame has applied such load only at one edge of the upper convolution of each coil spring. The marginal springs of such a prior assembly have therefore exerted their normal load-bearing action substantially independently of each other and in substantially the same manner as the other or central coil springs of the assembly, it being observed that the coiled tie wires heretofore extended between the upper ends of the various coil springs have had as their purpose the maintenance of the proper location of the upper ends

of the springs rather than the distribution of load therebetween.

While the construction of spring assemblies in accordance with the conventional methods hereinbefore set forth has produced satisfactory functioning of such assemblies in use, it has necessitated the location of the coil springs in what may be termed a practically side by side relationship so that a load imposed upon the top of the assembly would invariably be applied directly to the top or upper convolution of a coil spring or to tops of a plurality of adjacent coil springs. Thus a relatively large number of coil springs of relatively great individual strength has been required in each spring assembly, and a correspondingly large amount of material has been required for the cross-ties or tie wires and for the border wire or frame.

In view of the foregoing it is an important object of this invention to reduce the number as well as the individual strength of the coil springs required in such spring assemblies, and in particular, it is an object of this invention to reduce the amount of metal required for springs and other parts in the production of such assemblies.

It is recognized that the ultimate weight-supporting action attained in prior spring assemblies is desirable and advantageous, and it is a further object of this invention to enable this action to be attained through the use of a substantially reduced number of coil springs in each spring assembly, to thereby reduce the amount of spring metal required; and objects related to the foregoing are to enable an increased spring spacing to be used; to enable the size of the wire used in the coil springs of such assemblies to be reduced; to enable the applied load to be efficiently distributed to a number of the coil springs of a spring assembly; to accomplish such weight or load distribution by means which acts as an edge or border reinforcement along one or more edges of the assembly; to enable such load distribution to be extended both laterally and longitudinally of the spring assembly; and to attain greater distribution of such load in one of such directions, as for example, longitudinally of the assembly.

Further objects of this invention are to materially reduce the number of individual parts required in the production of spring assemblies of the aforesaid character, and to simplify and reduce the number of operations involved in the assembly of such parts.

It is a further object of this invention to so construct and arrange a load distributing structure in a spring assembly that this structure may

be made from a material such as wood, and a related object is to enable this supporting structure to be constructed as a unit to be thereafter placed in position on the tops of the coil springs of the spring assembly.

In many of the uses of spring assemblies of the kind to which this invention relates, and particularly in the use thereof in box springs and the like, there is often a concentration of weight or load in a particular portion of the assembly, as for example, at a point substantially midway between the ends of a box spring, and another object of the invention is to afford a spring assembly wherein such areas of concentrated load may be properly sustained even though the spacing of the individual springs of the assembly is relatively great; and an object related to the foregoing is to enable such concentration of load to be effectively supported where a weight distributing structure is associated with the upper ends of the coil springs of such an assembly.

A further object of the invention is to associate the individual coil springs of an assembly with the border members of the load distributing upper structure in such a manner that the springs will be held at all times in positions beneath such border members, thereby to assure straight and neat side edges on the box springs or the like in which such spring assemblies are used; and objects related to the foregoing are to enable the springs to be associated with the weight distributing structure in such a way that sharp ends of the wires or other securing devices are shielded and concealed so as to prevent injury to the upholstering applied to such assemblies, and to accomplish this in a manner which is conveniently adaptable to factory production methods.

Other and further objects of the present invention will be apparent from the following description and claims and are illustrated in the accompanying drawings which, by way of illustration, show preferred embodiments and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

Fig. 14 is a sectional view taken along the line 14—14 in Fig. 13.

In the form chosen for disclosure in Figs. 1 to 7, the invention is embodied in a spring assembly 10 adapted particularly for use in a bed spring of the box type, and in such use it will be recognized that an upper covering of upholstery or padding will be provided over the spring assembly 10 in the conventional manner. The spring assembly 10 is rectangular in form and embodies a relatively rigid bottom frame 12 constructed from wood in accordance with the usual practice to afford side rails 14, end rails 16 and spaced intermediate cross rails 18. The arrangement and proportioning of the cross rails 18 is, however, somewhat different from a conventional bottom frame in that the spacing of the rails, which in turn controls the spacing of the vertical coil springs 20 in one direction, is considerably greater than usual:

The coil springs 20 are of the type commonly employed in mattresses, cushions and the like and include end convolutions of substantially equal diameter arranged in planes parallel to the axis of the spring, and the intermediate convolutions are arranged spirally so as to be of a slightly smaller diameter. The springs 20 are supported in an upstanding relation on the cross rails 18 of the bottom frame 12 in laterally spaced relation and in rows extending longitudinally and transversely of the bottom frame, and such mounting of the springs 20 may be attained in any manner which affords a relatively stable and strong connection between the lower end convolution of each spring and the rail upon which it is supported. As herein shown such mounting is effected in accordance with one known method wherein a pair of spaced horizontal bores 24 are formed in a rail 18, Figs. 5 and 7, on opposite sides of the desired location of the center-line of a spring 20, and the end of the lower end convolution of a spring 20 is inserted, first through one of these bores 24 and then through the other of the bores 24, thereby to afford a supporting connection between the rail 18 and the lower end of the spring 20.

As hereinbefore pointed out, the spacing of the springs 20, or the rows thereof, is substantially greater than in prior spring assemblies of the type to which this invention pertains, particularly in a direction longitudinally of the assembly, thereby to materially reduce the amount of steel required in the production of an assembly of a selected size and loadbearing capacity, and in accordance with the present invention this result is attained in such a way that in addition to the reduction in the number of springs, the size or gage of the wire used in the springs is also capable of material reduction. Thus, in accordance with this invention, the springs 20 have a load-distributing top structure 30 associated with their upper ends and this top structure is so constructed and arranged as to minimize the amount of metal employed in the assembly. To this end a plurality of strong, yet relatively bendable slats 34 and 36 are extended across the tops of at least certain of the rows of springs 20, and in the present instance these slats are extended longitudinally of the spring assembly. The arrangement is such that the slats 34 are disposed over the respective longitudinal rows of springs, with each slat preferably arranged substantially symmetrically with respect to the central vertical plane of the row

of springs upon which it is supported, thereby to assure efficient application of the load from each slat 34 to the supporting springs 20.

In accordance with the present invention, the slats 34 and 36 which are included in the load distributing structure 30 are initially assembled as a unit which is thereafter put in position on the tops of the coil springs 20 of the spring assembly. In accomplishing this purpose, the slats 34 and 36 are positioned so that their opposite ends overlie transverse slats 38, and the slats 34 and 36 are secured to the transverse slats 38 by any suitable means such as nails 40. When the load-distributing assembly which is thus afforded is placed in position on the tops of the springs 20, the upper end convolutions of the springs 20 are secured to the slats 34 in such a manner that the springs 20 are held in the proper relation to the slats. As herein shown this is accomplished by means including transversely extending connecting wires or cross wires 42 and 42' which are so associated with the slats and with the upper end convolutions of the springs 20 that these parts are held in the desired relation to each other. Thus, as shown in Figs. 4 and 5, the cross wire 42 has one of its ends extended downwardly through a marginal slot 44 formed in one of the marginal slats 34 and this end of the wire 42 is bent about the upper end convolution of the corner spring 20 and is then extended upwardly through the slot 44 and bent laterally as at 46. The wire 42 is extended entirely across the tops of all of the slats 34 and 36, as is best shown in Figs. 1 and 4, and the other end of the wire 42 is connected to the opposite marginal slat 34 and to the other corner spring 20 in the manner just described.

It will be evident that adjacent to the ends of the spring assembly, the intermediate or secondary slats 36 are supported from the primary slats 34 through the medium of the transverse slats 38, and it is for this reason that it is possible to extend the wires 42 across the tops of the slats 36. In the intermediate portions of the length of the spring assembly, however, the cross wires 42' are utilized to support the intermediate slats 36. Thus as shown in Figs. 1 and 4 the cross wires 42' have their ends 46' secured to the upper convolutions of the marginal springs and to the marginal slats 36 in the same manner as hereinbefore described with respect to the wires 42. The wires 42' are, however, arranged so as to extend over the tops of the primary slats 34 and beneath the bottoms of the intermediate slats 36. Thus when a load is impressed upon one of the intermediate slats 36, this load is transmitted to the cross wires 42' and thence to the primary slats 34 on opposite sides thereof.

The foregoing arrangement of the cross wires 42 and 42' is such that one edge of the upper end convolutions of the marginal springs 20 is in each instance held in a predetermined relation to one of the slats 34, and means is associated with the cross wires 42 and 42' to hold the other or opposite edge portions of the marginal springs, and the opposite edge portions of all of the other springs in the proper relation to the slats. For this purpose a plurality of longitudinal tie wires 48 are provided, and each tie wire 48 has its opposite ends extended around the end slats 38 as indicated at 50 in Figs. 4 and 6 so as to be anchored to the end slats. One longitudinal tie wire 48 is disposed adjacent to the inner edge of each marginal slat 34 so as to be disposed over the points where the inner edges of the upper

convolutions of the marginal springs 20 pass beneath the cross wires 42 and 42'; and two such longitudinal tie wires 48 are associated with each of the other slats 34 so as to be disposed on opposite sides thereof in substantially the same relation as hereinbefore described with respect to the other tie wire 48.

The tie wires 48 are utilized to afford a connection between the cross wires 42 and 42' and the upper end convolutions of the springs 20 and this is accomplished in the manner shown in Figs. 4 and 6. As there shown it will be clear that the wire 48 is extended across the top of the end convolution of the spring and is then extended downwardly under the end convolution and upwardly over the cross wire 42, the wire 48 being then extended downwardly beneath the end convolution and then upwardly and across the top of the end convolution and toward the next spring in the same longitudinal row of springs. Thus a substantially V-shaped connection 52 is afforded between the end convolution of the spring 20 and the cross wire 42 or 42'. If desired the V-shaped portions 52 in the longitudinal tie wires 48 may be formed in the tie wires 48 before they are mounted in position on the spring assembly, and the desired association between the springs 20, the tie wires 48 and cross wires 42 may be effected by first inserting the V-shaped portions 52 through the upper convolutions of the springs and thereafter passing the wires 42 or 42' across the tops of the slats 34 and through the V-shaped connecting portions 52. When the cross wires 42 and 42' and the longitudinal tie wires 48 have been mounted and connected as hereinbefore described, the upper ends of the springs 20 are firmly held in place in the proper relation to the slats 34 which are to be supported thereby, and this connection between the springs 20 and the slats 34 is such that the transmission of load to the springs is accomplished in a highly effective manner.

It has been pointed out hereinbefore that the slats 34 and 36 are bendable and with the construction herein shown the stresses and strains are applied to these slats in such a manner that the load will be properly supported thereby even in the event that such slats are made from wood. It will be recognized of course that the slats may in some instances be made from other materials such as those formed from wood or bagasse in the manner disclosed in the Mason Patent No. 1,663,505 patented March 20, 1928. In other instances where metal is readily available, this material may be utilized in making the various slats of the upper supporting or load distributing structure 30, and when this is done, the resulting spring assembly will accomplish at least some of the objectives of this invention, for although metal would not in such an instance be conserved, there would, nevertheless, be a material simplification of assembly operations and a reduction in the number of individual parts required.

Where the load distributing structure 30 is formed in the manner hereinbefore described, the application of a load to the spring structure results in distribution of this load over a number of the springs 20, and hence these springs do not function as individual load supporting elements, but rather cooperate with each other in supporting any load which may be applied. Thus if a load is applied to one of the marginal slats 34, as for example at the midpoint thereof, this load will tend to bow the marginal slat 34 downwardly and while most of the load will be trans-

mitted to the two adjacent springs 20, the bowing action of the slat 34 will also apply a smaller portion of the load to all of the other springs which support this particular slat 34. As the springs 20 beneath the particular slat 34 are compressed, the cross wires 42' will act to a limited extent to impart a slight downward movement to the corresponding portions of the next adjacent slat 34, so that at least a small portion of the load will be applied to the next slat 34 and thence to the springs 20 associated therewith.

In the event that a load is applied to one of the intermediate slats 36, this slat will also tend to bow downwardly in a manner similar to the action just described with respect to the slats 34, and since the intermediate portions of the slats 36 rest upon the cross wires 42', such downward bowing of the slat 36 will be transmitted through the cross wires 42' to the primary slats 34 on opposite sides of the loaded slat 36. Thus the load impressed on this slat 36 will be transmitted to the adjacent slats 34 and thence to the associated springs 20. The load which is thus supported will of course be distributed over a relatively large number of the springs 20 in the general manner hereinbefore described. The connection which is afforded between the slats 36 and the slats 34 is of course bendable in character so that the distribution of the load transversely of the spring assembly is somewhat less in extent than the distribution in a longitudinal direction, and by this arrangement it has been found that the spring assembly is more effective and desirable in normal uses thereof. It will be observed that the marginal slats 34 serve to afford a uniform and adequate support along the longitudinal edges of the spring assembly, while the transverse or end slats 36 accomplish a similar function along the ends of the spring assembly, and as a result it has been found that the spring assembly of this invention is particularly suited for use in a production of box springs.

In some instances the spring assemblies of this invention may be subjected to relatively concentrated loads in particular portions thereof, and while in such cases the load distributing structure 30 will function to effectually distribute the load to a relatively large number of springs 20, the resulting bowing of the slats 34 and 36 may be considered objectionable by some users. For use in such instances the invention may be embodied in the form illustrated in Figs. 8 to 12 of the drawings. As therein shown the invention is incorporated in a spring assembly 10A which is in most respects similar to the spring assembly 10 of Figs. 1 to 7. The spring assembly 10A is, however, adapted to support loads concentrated near the midportion of the length of the spring assembly, thereby to adapt the same for use in heavy duty box springs or the like.

The spring assembly 10A may have the bottom frame 12A thereof constructed in any suitable manner, as for example, in the same general manner as the frame 12 of Fig. 2, and a plurality of coil springs 20A are distributed and mounted on the cross rails 18A of the bottom frame 12A in the manner disclosed in Figs. 1 to 7 so as to support an upper load-distributing structure 30A which conforms in most respects to the top structure 30. The top structure 30A includes parallel longitudinal slats 34A and 36A connected by end rails 38A in the same manner as in the structure 30, and the springs 20A are associated with the slats 34A in a generally similar manner. It will be observed however that the springs asso-

ciated with the outer or border slats 34A are somewhat different in form and these springs are therefore indicated as springs 20B. Each spring 20B, as best shown in Fig. 12, is formed with an upwardly bent positioning bow 60 in one side of the upper convolution thereof, and the positioning bow 60 is so formed and related to the upper convolution of the spring that the bow 60 may engage the inner side edge of the border slat 34A which is supported by the spring. The arrangement is such that when the bow 60 is thus engaged with the inner edge of the border slat 34A, the outer edge of the upper convolution of the spring 20B is disposed entirely beneath the border slat. With this arrangement it will be clear that the upper convolution of the springs 20B cannot become displaced in an outward direction relative to the border slats 34A, and hence straight and smooth border edges along the sides of the finished and upholstered mattress are assured.

The springs 20A and 20B are secured in predetermined relation to most of the slats of the load-distributing frame 30A in substantially the same way as in the other embodiment of the invention, there being wires 48A extended between the end slats 38A on each side of each slat 34A with the exception of the two edge or border slats. The wires 48A have V-shaped portions 52A formed therein at points spaced to correspond with the longitudinal spacing of the springs 30A, and these V-shaped portions 52A are inserted downwardly through and then outwardly and upwardly with respect to the upper convolutions of the springs 20A as in the other embodiment. Transverse or cross wires 42A are extended over the slats 34A and through the V-shaped portions on opposite sides of each slat 34A so as to hold the upper convolutions in position with respect to these slats. It will be observed that in this embodiment of the invention all of the cross wires 42A are similarly related to the slats 34A and 36A, the wires 42A in each instance being extended beneath the intermediate slats 36A in supporting relation to such slats 36A.

The ends of the cross wires 42A are secured to border slats 34A and to the upper convolutions of the related springs 20B, but in this embodiment of the invention the relationship is such that a longitudinal tie wire as 48 is not required along the border slats. Thus, as shown in Figs. 8 and 12, each border slat 34A is formed with notches 44A in the outer edge thereof in positions opposite the outer edges of the upper convolutions of the respective springs 20B. Thus, at each spring 20B, the adjacent end of the adjacent cross wire 42A may be passed outwardly through the positioning bow 60 of the spring 60 20B, across the top of the border slat 34A, and then downwardly through the slot 44A and through the outer convolution of the spring. This end of the wire 42A is then bent upwardly and inwardly, and is inserted through the adjacent positioning bow 60, as shown at 61 in Fig. 12. Thus, the positioning bow 60 serves to hold the end 61 of the wire 42A in a horizontal or non-projecting relation which is such that this end 61 cannot tear the upholstery or project upwardly and outwardly through such upholstery. Such an arrangement or formation of the connection between the wire 42A and the spring 20B is relatively simple and the required operations may be quickly and easily performed by the workman. This mode of attachment of the

wire 42A to the springs 20B also establishes a cooperative action between the wire 42A, the bow 60, the slot 44A and the spring 20B which results in proper positioning of the spring 20B with relation to the border slat 34A at all times, and this relationship or positioning is not disturbed by normal movements or use of the spring assembly.

In this embodiment of the invention the springs 20A and 20B are disposed in longitudinally and transversely arranged rows which are spaced apart in the same manner as in the other embodiment, and the springs 20A and 20B are similarly arranged to support the slats 34A while the intermediate slats 36A are supported by the cross wires 42A. Where a particular portion or area of the spring assembly is to be subjected to relatively heavy and concentrated loads, the present invention provides for additional resilient support in such area. Thus, as shown in Fig. 8, a transverse row of springs 20C is disposed on a transverse bottom rail 18C substantially midway between the ends of the assembly, and this row of springs 20C is disposed midway between the two adjacent transverse rows of springs 20A and 20B. The springs 20C, however, are arranged beneath the slats 36A so as to afford direct support for these intermediate slats, and with this arrangement an even and uniform support for the top frame 30A is afforded.

The upper ends of the springs 20C are held in the desired relation to the slats 36A by means including V-shaped positioning portions 63 formed on opposite sides of the upper convolution of each spring 20C. The positioning portions 63 extend upwardly on opposite sides of the related slat 36A, as shown in Figs. 10 and 11, and a cross wire 65 is extended across the top of the slot 36A and through the V-shaped positioning portions. As herein shown the wire 65 is also extended across the tops of the slats 34A, but it will be obvious that the wire 65 might be extended beneath the slats 34A if desired. At its ends the wire 65 is extended across the tops of the border slats 34A and are bent downwardly through slots 66 formed in the outer edges of the border slats 34A. These ends are then passed inwardly beneath the slat 34A and upwardly and about the wire 65 just inwardly of the slat, and the extreme ends 65' of the wires 65 are bent downwardly as shown in Fig. 10 so as to avoid possibility of injury to the upholstery. Thus the springs 20C are held in the proper relation to the midpoints of the slats 36A by the cooperative action of the V-shaped positioning portions 63 and the cross wire 65; and the springs 20C cooperate with the springs 20A and 20B in the two adjacent transverse rows of springs to support loads which may be concentrated adjacent the midpoint of the length of the spring assembly.

In other instances the spring assemblies of this invention may be subjected to relatively concentrated loads in other areas thereof, as for instance, at any point along the side border edges, at the corners, or in the transverse or mid-portion of the assembly. It will be evident that the load distributing structures 30 or 30A may in many instances function to properly distribute the load in such instances, but in the event that undesired bowing of the slats occurs, the invention may be embodied in the form illustrated in Figs. 13 and 14 of the drawings. As there shown the invention is incorporated in a spring assembly 10D which is in many respects similar to

the spring assemblies 10 and 10A. The spring assembly 10D, however, is adapted to support loads concentrated in the transverse mid-portion of the spring assembly, at the corners thereof, or at any point along the side border edges thereof.

The spring assembly 10D has the bottom frame 12D thereof constructed, for example, in the same general manner as the frame 12 of Fig. 2, and a plurality of coil springs 20D and 20E are mounted in properly spaced relation on cross rails 18D of the bottom frame in the same general manner as in the two embodiments shown in Figs. 1 to 12, and these springs are arranged to support an upper load distributing structure 30D which conforms in most respects with the construction of the top structures 30 and 30A. The top structure 30D includes parallel longitudinal slats 55, 56 and 57 connected by end rails 38D in the same manner as in the top structure 30. The slats 55, 56 and 57 are of the same form and construction as the slats 34 and 36 of the first described embodiment of the invention, and a different identification is employed with respect to these slats merely by reason of the different manner in which the supporting springs are distributed with respect to the several slats of the top structure. Thus the slats 55 constitute the border slats of the top structure 30D, and a slat 56 is disposed 20 in the top structure next to each of the border slats 55 and on the inner side thereof. The next slat adjacent to the aforesaid slat 56 is identified as a slat 57, and since the top structure 30D includes an odd number of slats, the slats 56 and 35 57 are disposed in an alternate relation so that in the present case the top structure 30D includes a total of eleven slats.

It will be observed that in this embodiment of the invention a larger number of coil springs is utilized to support the top structure 30D and these springs are formed differently than in the embodiment shown in Figs. 1 to 8 and are associated with the slats in a different spacing and arrangement so as to thereby obtain a different more desirable weight supporting action, and in addition, the springs are secured to the slats of the top structure 30D in a different manner so that the longitudinal tie wires such as the wires 48 or 48A are eliminated, and through this arrangement it is possible to utilize the larger number of springs without materially increasing the amount of metal required in the construction of the spring assembly.

As herein shown the slats 55 are supported by coil springs 20D, while the other slats 56 and 57 are supported by springs 20E, and while all of these springs are generally similar in form, the upper convolutions of the springs 20D are formed somewhat differently than the upper convolutions of the springs 20E. Thus each coil spring 20D has an upwardly bent positioning bow 60D formed on one side of the upper convolution thereof in the same manner as the bow 60 hereinbefore described, and the positioning bow 60D is so formed and related to the upper convolutions of the spring that the bow 60D may engage the inner side edge of the border slat 55, and when the bow 60D is so positioned the outer edge of the upper convolution of the spring 20D is disposed entirely beneath the border slat. By virtue of this arrangement the upper convolution of the spring 20D is held against outward displacement relative to the border slat 55 and hence this upper convolution of the spring cannot project beyond the outer edge of the border slat. As a result

this form and relationship insures that straight and smooth border edges will be maintained along the sides of the finished and upholstered mattress.

The upper convolutions of each of the springs 20E is so formed as to provide upwardly extending positioning bows 63E disposed on opposite sides of the upper convolution, and these bows 63E are so proportioned that they may extend upwardly along opposite sides of a slat 56 or 57 which is to be supported thereby, the form and relationship being substantially the same as that shown with respect to the bows 63 of the spring 20C in Figs. 10 and 11. The several springs 20D and 20E are of course arranged so as to afford longitudinal rows and transverse rows of springs, and all of the springs in each transverse row thereof are held in association with the slats which are supported thereby through the medium of transverse or cross wires 65D which are associated with the bows 60D and 63E in a manner which will hereinafter be described in detail.

In the present embodiment of the invention the several supporting springs are arranged in such a way as to provide an odd number of transverse rows of springs for by this arrangement the provision of a transverse area of greater weight supporting strength across the mid-portion of the assembly is facilitated. In the present case seven such transverse rows of springs are afforded and such rows are identified as rows T₁ to T₇ respectively. It has been pointed out that this embodiment of the invention affords added weight supporting strength along the side edges, and for this reason the longitudinal rows of springs which support the border slats 55 are arranged to include one spring 20D in each one of the seven transverse rows T₁ to T₇. The longitudinal rows of springs 20E which support the slats 56 are arranged to afford one spring in row T₁, one spring in row T₃, one spring in row T₅ and one spring in row T₇, while the longitudinal rows of springs 20E which supports the slats 57 are arranged to have a spring in row T₂, a spring in row T₄ and a spring in row T₆. Hence it will be observed that there is a spring 20E located relatively close to each of the corner springs 20D and because of this arrangement it is found that additional resilient support is afforded at the corner of the assembly. Similarly, in the mid-portion of the spring assembly, that is in the portion supported by the transverse rows T₃, T₄ and T₅ the springs are relatively closely spaced, and in addition, as herein shown, the rows T₃, T₄ and T₅ are more closely spaced than the other transverse rows of springs.

As hereinbefore pointed out, a transverse or cross wire 65D is provided for each of the transverse rows of springs. These wires 65 are extended across the tops of all of the slats, and are threaded through the positioning bows 60D of the springs 20D and the positioning bows 63E of the springs 20E, and at the border slats 55, the ends of the wires 65D are extended downwardly through slots 44D and through the upper convolution of the border spring 20D. This end of the wire 65D is then extended upwardly through the slot 44D and back across the top of the slat 55. The end 61D of the wire is then extended through the positioning bow 60D in the same general manner shown with respect to the wire 42A and the end 61 thereof in Fig. 12, so as to be held down in a horizontal or a downwardly projecting position wherein the end 61D of the wire cannot injure the upholstery of a bed spring or the like in which the spring assembly is used.

After all of the cross wires 65D have been put in position, the tops of all of the springs are held against movement in one direction by the upstanding portions or bows formed thereon and in the other direction by the clamping action with which the upper convolutions of the springs are held against the slats by the action of the cross wires 65D. If desired the positioning bows 60D and 63D may be formed so as to be relatively high, thereby to facilitate the threading of wires 65D therethrough, and in such an instance the clamping action exerted on the slats by the wires 65D is of course reduced. When this is done, the desired degree of clamping action may be attained by striking each of the bows 60D and 63D with a hammer so as to thereby reduce the overall height of these bows and causes a slight bending of the wires 65 over the slats as indicated in Fig. 14 of the drawings.

From the foregoing description it will be apparent that the present invention materially reduces the number of coil springs required to produce a spring assembly, and this end is accomplished in such a manner that the individual strength of these springs may also be reduced. The spring assemblies which are thus provided serve to distribute the load both longitudinally and transversely of a spring assembly and this result is attained by a load distributing structure which may be formed from materials such as wood, thereby to minimize the use of metal in the spring assemblies when this is desired.

It will also be evident that the present invention enables the border springs to be held securely and accurately in position to thereby assure that the upper border edges of the box springs or the like in which the assembly is used will retain the desired uniform and straight edge throughout the useful life thereof; and this is accomplished by simple and effective means adapted for factory production methods. Moreover, the present invention affords a novel arrangement of the springs which results in proper support of concentrated loads in selected areas thereof, and this is accomplished in such a way that a desirable weight-supporting action is attained under all conditions of use.

Hence, while I have illustrated and described the preferred embodiments of my invention, it is to be understood that these are capable of variations and modification and I therefore do not wish to be limited to the precise details set forth, but desire to avail myself of such changes and alterations as fall within the purview of the following claims.

I claim:

1. In a spring assembly, a substantially rigid bottom frame, a plurality of coil springs supported in spaced and upstanding relation on said bottom frame and disposed in symmetrically arranged rows extending longitudinally and transversely of said frame, a plurality of flat and bendable slats, one of which is extended longitudinally along each longitudinal row of springs so as to rest on the tops of such springs, other slats extended parallel to and between said first mentioned slats, bendable cross wires supporting said other slats from said first mentioned slats, and longitudinal tie wires extending along the longitudinal edges of said first mentioned slats interconnecting the upper end convolutions of the springs to said cross wires to thereby maintain said first mentioned slats in predetermined relation to their supporting springs.

2. In a spring assembly, a bottom frame, a

plurality of coil springs mounted in spaced up-standing relation on said bottom frame in positions affording spaced longitudinal and transverse rows of springs, a load-distributing structure disposed on the tops of said springs and comprising a plurality of parallel longitudinally extending flat slats made from wood and at least certain of which are rested directly upon the upper ends of a plurality of the springs, and end slats made from wood and respectively extended along and connected to the opposite ends of said parallel slats and supported thereby, cross wires connected between the outer ones of said parallel slats and affording load-transmitting connections between adjacent parallel slats, and longitudinal tie wires extended between said end slats and cooperating with said cross wires to secure the upper ends of said springs in predetermined relation to the slats supported thereon.

3. In a spring assembly, a bottom frame, a plurality of coil springs mounted in spaced up-standing relation on said bottom frame in positions affording spaced longitudinal and transverse rows of springs, a load-distributing structure disposed on the tops of said springs and comprising a plurality of parallel longitudinally extending flat slats made from wood and at least certain of which are rested directly upon the upper ends of a plurality of the springs, cross wires connected between the outer ones of said parallel slats and affording load-transmitting connections between adjacent parallel slats, and longitudinal tie wires cooperating with said cross wires to secure the upper ends of said springs in predetermined relation to the slats supported thereon.

4. In a spring assembly for bed springs, cushions and the like, a substantially rigid bottom frame, a plurality of primary coil springs secured at their lower ends on said bottom frame and disposed in spaced relation and in rows extending longitudinally and transversely of said bottom frame, a load-distributing structure carried on the upper ends of said springs and including a plurality of elongated primary slats and a plurality of secondary slats disposed in parallel and alternate relation with certain of the primary slats disposed along the opposite side edges of the load-distributing structure and constituting border slats, said primary slats being disposed along and rested on the certain of the respective longitudinal rows of springs, the border springs which support said border slats having upwardly bent positioning portions formed in their upper convolutions thereof and disposed in abutting relation to the inner edges of said border slats to prevent outward displacement of the outer edges of said upper convolutions beyond the outer edges of said border slats, means including cross wires securing said springs to said slats, said cross wires being extended through the upwardly bent positioning portions of the respective border springs and across said border slats and being connected to the outer portions of the upper convolutions of said border springs, and a plurality of secondary coil springs supported on said bottom frame and disposed in supporting relation to said secondary slats.

5. In a spring assembly for bed springs, cushions and the like, a substantially rigid bottom frame, a plurality of coil springs secured at their lower ends on said bottom frame and disposed in spaced relation and in rows extending longitudinally and transversely of said bottom frame, a

load-distributing structure carried on the upper ends of said springs and including a plurality of elongated primary slats and a plurality of secondary slats disposed in parallel and alternate relation with certain of the primary slats disposed along the opposite side edges of the load-distributing structure and constituting border slats, said primary slats being disposed along and rested on at least certain of the respective longitudinal rows of springs, the border springs which support said border slats having upwardly bent positioning portions formed in their upper convolutions thereof and disposed in abutting relation to the inner edges of said border slats to prevent outward displacement of the outer edges of said upper convolutions beyond the outer edges of said border slats, means including cross wires securing said springs to said primary slats, said cross wires being extended through the upwardly bent positioning portions of the respective border springs and across said border slats and being connected to the outer portions of the upper convolutions of said border springs.

6. In a spring assembly for bed springs, cushions and the like, a substantially rigid bottom frame, a plurality of coil springs secured at their lower ends on said bottom frame and disposed in spaced relation and in rows extending longitudinally and transversely of said bottom frame, a load-distributing structure carried on the upper ends of said springs and including a plurality of elongated slats disposed in parallel relation with certain of the slats disposed along the opposite side edges of the load-distributing structure and constituting border slats, said border slats and at least certain other of said slats being disposed along and rested on the respective longitudinal rows of springs, the border springs which support said border slats having upwardly bent positioning portions formed in their upper convolutions thereof and disposed in abutting relation to the inner edges of said border slats to prevent outward displacement of the outer edges of said upper convolutions beyond the outer edges of said border slats, means including cross wires securing said springs to the slats carried thereby, and said cross wires being extended through the upwardly bent positioning portions of the respective border springs and across said border slats and being connected to the outer portions of the upper convolutions of said border springs.

7. In a spring assembly for bed springs, cushions and the like, a substantially rigid bottom frame, a plurality of coil springs secured at their lower ends on said bottom frame and disposed in spaced relation and in rows extending longitudinally and transversely of said bottom frame, a load-distributing structure carried on the upper ends of said springs and including a plurality of elongated slats disposed in parallel relation with certain of the slats disposed along the opposite side edges of the load-distributing structure and constituting border slats, said parallel slats being disposed along and rested on the respective longitudinal rows of springs, the border springs which support said border slats having upwardly bent positioning portions formed in their upper convolutions thereof and disposed in abutting relation to the inner edges of said border slats to prevent outward displacement of the outer edges of said upper convolutions beyond the outer edges of said border slats, means including cross wires securing said springs to the slats carried thereby, said border slats having notches formed

in the outer edges thereof directly over the outer portions of the upper convolutions of the respective border springs, the end portions of said cross wires being extended through the upwardly bent positioning portions of the respective border springs and across said border slats and downwardly through said slots and about the outer portions of the upper convolutions of said border springs, and said ends of said cross wires then being extended upwardly through said slots and back across the tops of the border slats and through said positioning portions so that said ends are held downwardly in a protected relation.

8. In a spring assembly for bed springs, cushions and the like, a substantially rigid bottom frame, a plurality of coil springs secured at their lower ends on said bottom frame and disposed in spaced relation and in rows extending longitudinally and transversely of said bottom frame, and a weight-distributing top structure carried on the upper ends of said coil springs and comprising a plurality of bendable slats including border slats along the side edges of said top structure and intermediate slats disposed between said border slats, at least certain ones of which are extended across the tops of said coil springs of the respective longitudinal rows, the coil springs which constitute intermediate springs and which support said intermediate slats having upward bows formed in the upper convolutions to engage the side edges of the intermediate slats supported thereby, and means securing said slats to said tops of said springs and comprising transverse wires extended across the top of the slats which are supported by such intermediate springs and being extended through said bows, and said transverse wires being secured at their ends to said border slats.

9. In a spring assembly for bed springs, cushions and the like, a substantially rigid bottom frame, a plurality of coil springs secured at their lower ends on said bottom frame and disposed in spaced relation and in rows extending longitudinally and transversely of said bottom frame, a load-distributing structure carried on the upper ends of said springs and including a plurality of elongated slats disposed in parallel relation with certain of the slats disposed along the opposite side edges of the load-distributing structure and constituting border slats, said border slats and at least certain other of said slats being disposed along and rested on the respective longitudinal rows of springs, the border springs which support said border slats having upwardly bent positioning portions formed in their upper convolutions thereof and disposed in abutting relation to the inner edges of said border slats to prevent outward displacement of the outer edges of said upper convolutions beyond the outer edges of said border slats, each of the other of said springs having a pair of upwardly bent positioning bows formed in the upper convolution thereof and en-

gaging opposite side edges of the slat supported thereby, means including cross wires securing said springs to the slats supported thereby, the cross wires which are aligned with border springs being extended through the upwardly bent positioning portions of the respective border springs and across said border slats and being connected to the outer portions of the upper convolutions of said border springs, and the cross wires which are aligned with the other of said springs being extended through the pairs of positioning bows of such springs and across the tops of the slats intermediate the bows of each such pair of bows to hold the bows and the related slat in predetermined relation.

10. In a spring assembly, a substantially rigid bottom frame, an upper load distributing structure including a plurality of bendable longitudinal slats and a pair of cross slats connecting the ends of said longitudinal slats, the outside ones of said longitudinal slats constituting border slats, and a plurality of coil springs supported at their lower ends on said bottom frame and connected at their upper ends to said longitudinal slats and disposed in longitudinal and transverse rows in such a relation that each border slat is supported by one spring of each transverse row while all other of the slats are supported by springs disposed in alternate transverse rows of such springs.

11. In a spring assembly for bed springs, cushions and the like, a substantially rigid bottom frame, a plurality of coil springs secured at their lower ends on said bottom frame and disposed in spaced relation and in rows extending longitudinally and transversely of said bottom frame, a load-distributing structure carried on the upper ends of said springs and including a plurality of elongated slats disposed in parallel relation with certain of the slats disposed along the opposite side edges of the load-distributing structure and constituting border slats, said parallel slats being disposed along and rested on the respective longitudinal rows of springs, the border springs which support said border slats having upwardly bent positioning portions formed in their upper convolutions thereof and disposed in abutting relation to the inner edges of said border slats to prevent outward displacement of the outer edges of said upper convolutions beyond the outer edges of said border slats, means including cross wires securing said springs to the slats carried thereby, the end portions of said cross wires being extended through the upwardly bent positioning portions of the respective border springs and across said border slats and downwardly and about the outer portions of the upper convolutions of said border springs, and said ends of said cross wires then being extended upwardly and back across the tops of the border slats and through said positioning portions so that said ends are held downwardly in a protected relation.

GEORGE E. TAYLOR.
